UNITED STATES PATENT OFFICE.

WILLIAM R. WHITEHORNE, OF LEWISTON, MAINE.

COLOR PHOTOGRAPHY.

Application filed August 24, 1925. Serial No. 52,000.

My invention relates to color photography and involves a method by which such photographs can be taken and prepared with a minimum of time and a maximum of accuracy in color reproduction.

My invention may be differentiated from former methods first by the general statement that it does not depend upon the use of screens or filters. The advantage of this in the saving of time and the simplification of apparatus is obvious. My invention is perhaps most particularly characterized by my use of one or more plates, films or other sensitized media which are particularly insensitive with regard to certain parts of the spectrum. The matter of differentiated sensitivity, generally speaking, is not new, but in my invention this matter of a special or characteristic insensitivity is made to play a somewhat different part than has heretofore been accomplished or attempted.

I have found that plates sensitized in certain manners, as will be hereinafter discussed, may be thereby rendered relatively insensitive to certain colors or wave lengths so as to show a very marked or characteristic band as readily appears from the spectrogram. Such plates have been developed for photography of special subjects, but usually with particular reference to their photographic power in general regions. This is usually obtained at the expense of lack of sensitivity in certain other regions, which lack of sensitivity while undesirable, has not been a serious defect for ordinary photographic purposes.

In accordance with my invention I utilize this very incident of insensitivity as a means of obtaining the desired color effect, that is to say, by deliberately employing a plate which is quite definitely insensitive to a certain color I am able by my method to intensify that very color in my ultimate picture to which a selected plate is comparatively blind.

As is well known to those skilled in this art, there is great difficulty in obtaining a uniform and faithful reproduction in the colors of different subjects. My invention makes it possible to specialize for any subject in that color or its shade which is most prominent and characteristic and which hence demands the most perfect depiction.

In order to make my invention clear I have attempted in the accompanying draw-

ings to illustrate certain characteristic media and those steps by which such photographs can be produced. To these I shall make reference by the usual characters similarly applied throughout.

In the drawings I have selected as an object to be photographed what may be considered as a child's ball or plaque striped in different colors. While this does not involve the depiction of intermediate colors or shadings, it is believed that the production of these intermediate effects will be seen by those skilled in the art to follow naturally according to the principles disclosed. In these drawings:

Fig. 1 is intended to represent an object such as a disk or ball striped vertically in different colors.

Figs. 2 and 3 represent photographic negatives thereof.

Fig. 4 is a diagrammatic illustration of a composite or doubling of these negatives.

Figs. 2^a, 3^a and 4^a indicate spectrograms showing the light intensities of these plates.

Figs. 5, 6 and 7 indicate prints from the plates of Figs. 2, 3 and 4.

Figs. 8, 9 and 10 represent these prints as toned or dyed.

Fig. 11 indicates the transmitted color values of these three prints when superimposed.

Figs. 12, 13 and 14 represent a pair of negatives and their composite diagram corresponding to Figs. 2, 3 and 4, but involving modified procedure.

Figs. 12^a, 13^a and 14^a indicate a spectrogram of the light intensities of the plates indicated in the preceding Figs. 12, 13 and 14.

Figs. 15, 16 and 21 represent prints therefrom corresponding to Figs. 5, 6 and 7.

Fig. 17 indicates a print from the plate of Fig. 21, giving its reversal.

Figs. 19, 20 and 18 represent the colored prints of Figs. 15, 16 and 17, and

Fig. 22 represents the transmitted light values of the superimposed colored prints.

The object X shown in Fig. 1 is merely selected for convenience of illustration and while its colors are banded rather than otherwise distributed, as in most pictures or scenes, it will be understood that the principles involved are the same.

As suggested earlier herein, my method offers unusual possibilities for selection in

- the reproduction of predominant or important colors in any selected subject or view to be photographed. While therefore the object X shown in Fig. 1, does not call for any particular intermediate color treatment, we may assume that it is desired to favor a green color as would be the case if a landscape was taken in which trees and plants predominate.
- 10 In order therefore to favor the green or its important component yellow, I employ a plate B which has been bathed or otherwise prepared with a solution which renders it substantially insensitive to the green yellow region. This may be readily seen in a spectrogram as indicated in Fig. 3^a which shows a broad bright band through this region.
- With this plate I use a plate A, which may be an orthochromatic plate, which shows a 20 considerably differentiated spectrum band as indicated in Fig. 2^a. These plates may be exposed in any desired manner. Very conveniently they may be assembled in tandem in a pack or loaded into a plate holder in 25 superimposed position and the picture may be then made in the usual manner in an ordinary camera at substantially the same speeds that ordinary pictures would be taken.
- While I mention this superimposed exposure of the plates as convenient in the practice which I have followed as it assures registry of the prints, I would explain that any filtrative effect, such as has been heretofore stressed in certain processes depending 30 upon filtration, may be relatively ignored, for the purposes of the present application, as my invention is not dependent upon such an action and as such an action is wholly incidental to the more important factors 35 which I will now describe.
- While the two negatives A and B heretofore described are very considerably differentiated chromatically, and in one phase of my invention capable of use in two color work where it is desired to get more faithful 40 reproduction of the natural colors a third color system is preferable as is general in color photography.
- In the practice of my invention, therefore, instead of attempting to take a third negative at the time the picture is snapped, I take my two negatives A and B and superimpose them as diagrammatically illustrated 45 in Fig. 4. In this figure it will be seen that the densities of the negatives or the indicated intensities in the spectrum as indicated by the lighter portion in Fig. 4^a, is 50 very much narrower and a print from the superimposed negatives A and B gives a print or positive in which the yellow is very 55 strongly accentuated as indicated in Fig. 7. If now prints be taken from negatives A and B, the prints will appear substantially as 60 shown in Figs. 5 and 6, in which the stripes 65 are considerably differentiated.

These prints 5, 6 and 7 may be considered as lantern slide prints or may be of any other material adapted for the purpose.

I then dye or tone the prints A¹, B¹, (AB)¹, as for example, red, blue and yellow, 70 respectively, as indicated in Figs. 8, 9 and 10.

If now these plates or members indicated in their dyed condition as A², B² and (AB)², are superimposed the transmitted light will 75 make the object photographed come out substantially in its original color as I have attempted to indicate in Fig. 11. In that figure it will be seen that the black stripe of the ball having come out strong in each of the 80 prints shows the combined red and yellow very much darkened by the blue, so that the effect is a dark brown which is supposed black in value. The green stripe is made up of the superimposed blue and yellow of 85 prints B² and (AB)² which by reason of their careful selection may be made to show the desired green with very great faithfulness. The red stripe is clearly presented by the red of plate A². The yellow is strongly 90 presented by the plate (AB)² and the blue by the plate B².

It will be particularly noted that the yellow of the plate (AB)² comes from the overlap of the spectrum values of plates A and B, 95 so that the ultimate slide member comes out with a very particular definition of yellow which was the very color to which the sensitized plate B was blind.

The plate selected for representation as 100 plate B and as indicated by the spectrum diagram 3^a happens to be what is known as a "pinorthol", which happens to give the particular band shown in the spectrum. In certain circumstances where some colors other 105 than green appear prominently, it might be desired to furnish plates of different characteristics for the purpose of favoring those colors in the final prints or slides.

In selecting an example in accordance with 110 my invention for this purpose, as where the scene involves a sun set or desert sands or highly colored rocks or cliffs, it might be desired to bring out the red-orange colors.

In treating this phase of my invention I 115 will explain somewhat of a variant of the practice indicated in my foregoing description. In the previous instance I described the use of a sensitized plate which was substantially insensitive to the color desired, by 120 taking a print from the combined negative so as to secure a narrowing of the bright band in the combined spectrum.

In the procedure which I will now describe 125 I will discuss a method by which I take two plates which includes one which is considerably sensitive to the color desired, but insensitive to some other color. I then proceed to take my composite negatives as indicated in Fig. 14, but take from them a print which 130

reverses the values and using this print as indicated in Fig. 17 as a negative, produce an ultimate print as in Fig. 18, which I use for the color to be less favored, as will be seen by the following.

If the plate A indicated in Fig. 12 be an ordinary plate, dyed for example with pinacyanol blue, its spectrogram (indicated in Fig. 12^a) will be dark in the red generally and dark in a narrow band of the blue green. As indicated in Fig. 13^a, the spectrogram of plate C while having a bright band in the red is sharply cut off between the blue and the red. In the composite therefore the print (AC)¹ will be light in the red and dark in the blue, while the print (AC)² (Fig. 17) from (AC)¹ (Fig. 21) will be dark in the red and light in the blue.

The print A² shown in Fig. 18 is then dyed or toned red; the print C² (Fig. 19) is dyed or toned blue; and the print (AC)³ (Fig. 20) is dyed or toned yellow.

Transmitted light of these combined plates will show a very good red and a somewhat yellowish green, or in other words, will express to advantage the red-orange and yellows at the expense of the green.

It will be seen from these two examples that my method involves peculiar possibilities in its utilization of chromatic differences in plates without screens, first, by a recognition of true possibilities of such differentiation, and second, by what might be called an additive subtraction as in the case of the using of a composite plate, and third, by the additional step of reversal of the print from the composite negative to supply the third color.

As additional instances of my process, plates, or films may be made up as follows:

For a two color picture I preferably use what we may call a pinacyanol blue plate as heretofore referred to, and an ordinary or ortho chromatic plate. These give an excellent separation of the red from the blue and the result is very satisfactory.

For a three color result from two plates, as hereinbefore described, I provide an erythrosine dyed plate and a pinacyanol dyed or a pinacyanol blue dyed plate. The latter is preferable for pictures in which there is a considerable amount of yellow. The erythrosine plate separates the yellow from the red better than the polychrome plate and the two plates of this character may be combined to produce a third plate as before described.

Where exposure can be made using three plates or surfaces in the original exposure, I find very satisfactory results come from the use of an erythrosine plate, a pinacyanol blue plate and a pinacyanol. Where pictures are taken in succession I substitute a pinorthol II for the pinacyanol. Where the plates are exposed in tandem it does not

seem to make much difference with the above named whether the pinacyanol blue plate is in the front or in the rear.

It will be obvious to those skilled in the art that different sensitizers may be selected or plates differently sensitized may be used to produce combined color plates which can thus be employed in the ordinary camera in ordinary photographic methods of picture taking. The preparation of lantern slides or other color photographs from such negatives is simple and may be done by ordinary contact printing and by ordinary methods of toning or dyeing. All such modifications and variants are to be understood as within the scope of my invention which I have defined in the following claims.

What I therefore claim and desire to secure by Letters Patent is:

1. In sensitized media for color photography, a pair of sensitized surfaces having a common color insensitiveness in one region of the spectrum and a different color insensitiveness in another part of the spectrum.

2. In a system of color photography the exposure of plural sensitized surfaces, one of said surfaces having a predetermined insensitiveness to a desired group of wavelengths, in reversing the negative so formed and printing therefrom to secure a colorable member or color photograph.

3. In a system of color photography, the production of a pair of photo negatives from sensitized media having common color insensitiveness in one region of the spectrum and a different color insensitiveness in another part, and in preparing a print combining the effect of the joint insensitiveness of the two negatives first mentioned.

4. In a system of color photography, the production of a pair of photo negatives including one of characteristic color insensitiveness, in producing a print from the composite negatives, and in preparing colored prints from the individual negatives and from the composite print.

5. In a system of color photography, the production of a pair of photo negatives from sensitized media having common color insensitiveness in one region of the spectrum and a different color insensitiveness in another part, and in preparing a print combining the effect of the joint insensitiveness of the two negatives first mentioned, and in taking colored prints from the said first mentioned negative and from the composite print.

6. In a system of color photography, the production of a pair of photo negatives including one of a predetermined color insensitiveness in producing a third print from the composite negatives, and in preparing colored prints from the individual negatives and from the composite print as a negative.

7. In a system of color photography, the

production of a pair of photo negatives each having a common color deficiency in one part of the spectrum and each having a different color deficiency in another part, and in preparing differently colored prints therefrom in predetermined supplementing chromatic balance.

8. In a multi-color photographic process the making of two chromatically differentiated exposure members, and in producing

therefrom a third chromatically differentiated member in color supplementing relation thereto. 15

9. In a multi-color photographic process the making of two chromatically differentiated negatives, and in producing therefrom three or more chromatically cooperative color plates for assembly.

In testimony whereof I affix my signature.
WILLIAM R. WHITEHORNE.
